Application May 26, 1954, Serial No. 432,570

9 Claims. (Cl. 255—28)

This invention relates to a method of alleviating vibratory forces and shock forces in a rotary drill column in an oil well and is directed to the construction of a drill collar for carrying out the method.

Shock forces and vibration, especially harmonic vibration, transmitted to a drilling column in an oil well from the rotary drilling bit at the bottom of the column commonly create such strain and fatigue in the metal of the drilling column as to cause structural failure or "twistoffs." The failures occur at screw threads which are the weakest points in the drilling column. More often than not the failures occur in the lower part of the drill column but they may occur in drill collar threads or tool joint threads at any level.

The factors that determine the frequency and amplitude of the vibration and of the shock forces include the rate of rotation of the drilling bit, the pressure applied to the drilling bit, the kind of formation encountered by the drilling bit, the slope of the formation, etc. Usually the forces involved tend to be excessive as the drilling bit makes the transition from one formation to another.

The rate of rotation of the drilling bit may vary from 40 R. P. M. to 500 R. P. M. or higher and, of course, vibration increases with the speed of rotation. Usually a relatively high rate of rotation is desirable but is not permissible because of the destructive effect of the resultant vibration.

The pressure imposed on the rotary bit varies from 300 to 2500 lbs. per inch diameter of the bit. Thus, the total pressure varies from $\frac{1}{2}$ ton to 25 tons. More than 10 tons is seldom necessary.

If the drilling bit pressure were obtained by placing most or all of the drill column under longitudinal compression, the result would be the creation of excessive and destructive stresses at the drill collars and tool joints in the drilling column. And a further result would be the likelihood of diverting the drilling from the desired direction. For these reasons the desired pressure at the rotary bit is provided by adding weight to the lower end of the drilling column. The added weight is obtained by a drill collar assembly consisting of a series of individual drill collars substituted for lengths of drill pipe at the lower end of the drilling column. Such individual drill collars are usually made by machining and boring solid lengths of steel to provide heavy tubes with relatively thick walls. The machining, and especially the boring, is expensive so that such individual drill collars are relatively costly items.

To avoid subjecting the drill pipe of the column to such excessive compressive stress with resulting fatigue and failure, the weight on the rotary bit should never exceed that of the drill collar assembly and preferably should normally be not more than half the weight of the drill collar assembly. Thus all compression in the drill column is confined to the drill collar assembly so that the major portion of the drill column is under tension rather than compression in the drilling of a deep well. It is apparent that the drill collar assembly will usually have considerable weight. A drill collar assembly as long as 180 feet and weighing as much as 8 tons is not unusual.

In some types of formations, such as brittle shales, gumbos and conchooidal-fracturing limestones, there is a definite upper limit to the bit pressure that can be used efficiently, higher bit pressures reducing the rate of

2

penetration. More often than not, however, there is reason to use a relatively high bit pressure along with a relatively high speed of rotation. Thus in some formations, such as limestone developing angular fractures, salt,

5 very hard sandstones or quartzites, and igneous rocks, the rate of penetration of the bit appears to increase as a straight line function with increase in bit pressure, irrespective of the rotating speed and volume of fluid circulated. Again in other formations such as soft sandstones, sandy shales and silts, the rate of penetration increases directly with weight on the bit if fluid circulation and rotational speeds are proportionately adjusted.

Some of the causes of vibration and shock may be readily understood by considering the manner in which 10 a drilling bit functions. At the proper bit pressure the drilling bit embeds itself in the formation just enough to permit it to chip away the rock in small fragments as the stem revolves. Inevitably, however, situations arise and persist for periods of time in which the bit 15 pressure is excessive for the particular formation. In that event, the bit will embed itself in the rock to such extent that it cannot cut itself free. Since the drilling bit cannot cut itself free it repeatedly jumps loose to cause a chattering action that strains the whole equipment. The tremendous weight of the usual drill collar 20 assembly is added to this chattering action. It is this kind of strain that commonly causes twistoffs with the penalty of added labor and loss of drilling time. To avoid such consequences drillers are commonly forced 25 to be very conservative in drilling speeds and pressures.

The present invention alleviates the effects of vibration, chatter, and other forces generated at the drill bit, by providing a drill collar construction which will cause such forces to be at least partially damped and dissipated at 30 the lower end of the drilling column. It is contemplated that each individual drill collar in the series of drill collars will absorb a portion of the forces transmitted thereto from below so that the series of drill collars in the drill collar assembly will have a desirable cumulative effect 35 on the engendered forces.

In general the desired effect is attained by mounting masses of material on the lower end of the drill column with freedom for movement of the masses relative to the drill column. Energy is diverted from the solid structure 40 of the drill column by transmission to these masses of material to cause independent movement thereof. Energy is dissipated, in part, by friction involved in the relative movements of the added masses. Energy dissipation also arises from the fact that the masses being largely free 45 from control move at random relative to the solid structure of the drill column, so that a vibratory or shock movement of the drill column structure in one longitudinal direction may result in an impact against a free mass moving in the opposite direction, energy being absorbed 50 in deceleration of the free mass.

In some practices of the invention the relatively movable mass of material incorporated in the structure of an individual drill column is in the form of one or more bodies of liquid. Liquid has a desirable damping action 55 and affords the advantage of minimizing the shocks involved in impacts of the relatively movable mass of material against the solid structure of the drill column.

In some practices of the invention further energy dissipation and further damping effect are achieved by the 60 combination of a confined body of liquid and a freely movable mass of solid material at least partially submerged therein. This combination not only affords the advantages peculiar to each of the two kinds of material, but also provides a certain dashpot action in the interference by the liquid with the movements of the solid material.

The solid material in the various practices of the in-

vention may comprise a small number of relatively large solid bodies or a large number of relatively small solid bodies and may even comprise finely divided solid material. An important advantage of combining liquid material with solid material is that it makes it possible to cause the solid material to seek any desired normal position within its range of vertical movement.

If a liquid is selected that is of lower specific gravity than the solid material immersed therein, the solid material will seek a normal position at the lower limit of its range of relative vertical movement. In such an arrangement the solid material responds primarily to upward components of movement of the drill column and has maximum freedom for upward movement in response to such upward components. If the liquid is selected for a higher specific gravity than the solid material to cause the solid material to float thereon, the solid material may be caused to seek a normal position at the upper limit of its range of relative vertical movement. Thus the solid material will respond primarily to downward components of movement of the drill column and will have maximum freedom for movement in response to such downward component.

If the liquid has a higher specific gravity than the solid material, the volume of the liquid relative to the volume of the confined space and the volume of the solid material may be selected to cause the solid material to tend to float at any desired intermediate level in its range of relative movement. The solid material will then have freedom for vertical movement in both directions from its normal position and will not make direct impact with the solid structure of the drill column unless it reaches one or the other of the two limits of its range of vertical movement.

It is apparent that a drill collar assembly made up of a series of individual drill collars may comprise a variety of individual drill collars for a variety of individual effects. Thus in some drill collars of the assembly masses of solid material will normally seek the lower limits of their ranges of movement; in other drill collars of the assembly, the masses of solid material will normally seek the upper limits of their ranges of movement. In any event, a drill collar assembly incorporating relatively movable masses of material in accord with the teachings of the invention will absorb, dissipate and dampen vibratory forces and shock forces to minimize the structural failures that are commonly caused by vibration and shock. Such a drill collar assembly will permit a higher than usual rate of rotation of the drilling bit with consequent higher than usual rate of penetration by the bit.

The various features and advantages of the invention may be readily understood from the following detailed description considered with the accompanying drawings.

In the drawings, which are to be regarded as merely illustrative:

Fig. 1 is a simplified diagrammatic view of a drill column in a bore hole with the lower end of the drill column provided with a drill collar assembly as taught by the present invention;

Fig. 2 is an axial section of a portion of the drill collar assembly in Fig. 1 showing the construction of an individual drill collar in the assembly;

Fig. 3 is a transverse section taken as indicated by the line 3—3 of Fig. 2;

Fig. 4 is a view, partly in side elevation and partly in section, showing a second form of individual drill collar that may be used in the drill collar assembly;

Fig. 5 is a transverse section taken as indicated by the line 5—5 of Fig. 4;

Fig. 6 is a view similar to Fig. 4 showing a third form of individual drill collar that may be used;

Fig. 7 is a similar view showing a fourth form of drill collar that may be used;

Fig. 8 is a similar view of another form of drill collar that may be used;

Fig. 9 is a similar view of a still further form of drill collar construction that may be used; and

Fig. 10 is a transverse section taken as indicated by the line 10—10 of Fig. 9.

Fig. 1 shows schematically an oil well bore 20 in which a drilling string or drill column 21 carrying a drilling bit 22 is rotated in the usual manner by the rotary table 23 of a drilling unit at the top of the well. The lower portion of the drill column 21 comprises a drill collar assembly, generally designated by numeral 24, which, in turn, comprises a series of individual drill collars 25. Any number of individual drill collars 25 may make up the drill collar assembly 24, the number being determined by the weight that is desired on the drilling bit 22.

Fig. 2 shows one embodiment of an individual drill collar, generally designated 25a, which may be incorporated in the drill collar assembly 24 of Fig. 1. The construction shown in Fig. 2 includes an inner steel tube 30 and a shorter outer steel tube 31 which together form an annular space or chamber 32. As best shown in Fig. 3 a series of I-beams 33 may be positioned longitudinally in the annular space 32 to serve as spacers and to provide reinforcement for the two tubes. The I-beams 33 may be attached to the inner steel tube 30 by welding.

The upper end of the inner steel tube 30 is threaded into a tool joint box 35 in a fluid tight manner. The fluid tight fit may be accomplished by threading the inner steel tube 30 in to the tool joint box 35 while the tool joint box is heated so that the tool joint box will shrink into a pressure fit with the inner steel tube. United with the tool box joint 35 by welding 36 is a sleeve extension 37 which embraces the inner steel tube 30 and is attached by welding 40 to the upper end of the outer steel tube 31 to close the upper end of the annular compartment 32. In the construction shown, the sleeve extension 37 has an end portion 41 of reduced diameter to fit into the end of the outer steel tube 31. The end of the outer steel tube 31 is bevelled as shown to permit the welding 40 to lie inside the desired maximum diameter.

In like manner the lower end of the inner steel tube 30 is threaded into a tool joint pin 44 in a fluid tight manner. Connected with the tool joint pin 44 by welding 45 is a sleeve extension 46. The sleeve extension 46 has a reduced end portion 47 that fits into the lower end of the outer steel tube 31 and is attached thereto in a fluid tight manner by welding 48 to form the lower end of the annular chamber 32.

It is contemplated that the annular chamber 32 will be partially filled with a suitable liquid in addition to containing the I-beams 33. Any suitable arrangement may be provided to make it possible to introduce liquid into the annular chamber and to drain the liquid out of the chamber when desired. For this purpose each of the two sleeve extensions 37 and 46 may have a short longitudinal bore 50 communicating with a radial bore 51 to provide a passage for communication between the annular chamber 32 and the exterior. The two radial bores 51 may be closed with suitable screw plugs 52 to confine a body of liquid in the annular chamber 32. Preferably the liquid level is slightly below the upper end of the annular chamber 32, for example, as indicated at 55, to provide room for thermal expansion of the liquid.

Any suitable liquid may be used, including relatively heavy liquids as well as relatively light liquids. For example, the liquid may be mercury, oil or water. In some instances it will be desirable to use a relatively light fluid having a low freezing point, for example, glycerine or alcohol.

If the annular chamber 32 contains mercury the total weight of the individual drill collar 25a including the mercury will be of the same order of magnitude as the weight of a conventional solid steel drill collar but the freedom for movement on the part of the confined mercury body will provide a desirable damping effect on

vibratory forces and shock forces. Upward movements of the drill column engendered by action of the drill bit will, of course, be opposed by the weight of the mercury and the forces involved must overcome the inertia of the mercury. Downward movements of the drill collar engendered by the drill bit, however, are not opposed by the total inertia of the mercury body because there is freedom for relative vertical movement between the mercury body and the confining structure of the drill collar.

In a downward movement of the drill column the confined mercury body tends to remain stationary but this tendency is opposed by the friction between the mercury and the vertical metal surfaces including the many vertical surfaces of the I-beams 33. In addition the tendency for the mercury body to remain stationary when the drill column moves vertically downward is opposed by the air body in the chamber 32 above the liquid level of the mercury. It is apparent that when the mercury column in the chamber 32 is lifted bodily by an upward thrust of the drill column and the upward thrust is abruptly terminated, the mercury will tend to continue its upward movement and will be decelerated by frictional resistance and by displacement of the air body and impact of the mercury against the upper end surfaces of the chamber 32.

There is, of course, a slight delay involved with respect to the impact of the mercury body against the upper end wall of the chamber. If the drill column is vibrating, the vibratory upward thrust of the drill column will be followed immediately by a downward thrust and the impact of the mercury against the upper end wall of the chamber may occur at a time to oppose the downward movement of the drill column. Thus, more often than not, the mercury will oscillate out of phase with respect to the vertical vibratory movement of the drill column, the out of phase relationship providing a desirable damping action.

The individual drill collar 25b shown in Figs. 4 and 5 is largely identical with the first described embodiment, as indicated by the use of corresponding numerals to indicate corresponding parts. In this second embodiment of the invention the I-beams are omitted and the annular chamber 32 of the drill collar structure is occupied by a single solid metal body together with a body of mercury in which the solid body is at least partially submerged. The solid metal body is in the form of heavy tubular member 60, which may be a heavy steel tube dimensioned for free longitudinal movement in the annular chamber 32. The heavy steel tubular body 60 is immersed in a body 61 of mercury and tends to float on the mercury body. The mercury may extend to a liquid level 62, for example, which is at a sufficient elevation to hold the tubular body 60 against the upper end of the chamber 32 under static conditions. It will be noted that there is a substantial air space above the liquid level 62 which not only allows for thermal expansion of the tubular body 60 and of the mercury body 61, but also provides space for surging action of the mercury.

Since the metal tubular body 60 is normally in contact with the upper end of the annular chamber 32 it is apparent that the tubular body 60 will respond directly and bodily to downward thrusts of the drill column and it is further apparent that there is room for a substantial range of relative downward movement of the tubular body 60 from its normal static position relative to the structure of the drill column.

Downward movement of the tubular metal body 60 relative to the drill column is opposed, first, by the tendency of the tubular body to float and, second, by the resistance of the mercury to upward displacement through the narrow longitudinal spaces inside and outside of the tubular body 60. There is a certain dashpot action involved in the restriction of the upward flow of the mercury.

It is apparent that an abruptly terminated downward thrust on the part of the drill column will result in con-

tinued downward movement of the solid tubular body 60 in an annular chamber with consequent displacement of mercury and that the solid tubular body will then seek to return to its normal upper floating position. The solid tubular body returns to its normal upper position after an appreciable time delay and in many instances the solid tubular body 60 will make this upward return movement in synchronism with a downward thrust of the drill column to oppose the downward thrust. Thus, here again, the freedom for a relatively movable mass of material to reciprocate out of phase with the longitudinal reciprocation of the drill column is important in modifying the action of the drill column by damping effects and energy dissipation.

The third form of the invention comprising the individual drill collar 25c shown in Fig. 6 is identical with the form shown in Fig. 4 as indicated by the use of identical numerals to designate identical parts. In this instance, however, the body of mercury is replaced by a body 66 of relatively light liquid, for example, water, which liquid has a normal static level 67. Since the liquid is of much less specific gravity than the solid tubular body 60, the tubular body normally seeks a position at the bottom of the annular chamber 32 as shown in Fig. 6. There is freedom for relative movement of the body of liquid 66 because the normal liquid level 67 is spaced substantially below the upper end of the annular chamber.

In the embodiment of the invention shown in Fig. 6, the solid tubular body 60 responds directly to upward thrusts of the drill column and has a range for relative upward movement in response to such thrusts. The upward movement of the solid tubular body 60 is opposed by gravity and by frictional resistance. It is also to be noted that any upward movement of the solid tubular body 60 that contracts the space above the normal level 67 will be opposed by the compression of air body therein. If desired this air may be normally under pressure substantially above atmospheric.

If the relative upward movement of the solid tubular body 60 in the annular chamber 32 results in downward displacement of the liquid into the lower end of the chamber, there will be a certain dashpot action to resist both the relative upward movement and the return downward movement of the solid tubular body since the liquid is forced through restricted longitudinal spaces inside and outside of the solid tubular body. Here again it is apparent that the freedom for the solid tubular body 60 to reciprocate vertically out of phase with the vertical reciprocations of the drill column is important.

Fig. 7 shows another embodiment of the invention comprising an individual drill collar 25d which is identical with the previously described individual drill collar 25b of Fig. 4 except for the quantity of mercury employed. In Fig. 7 the body of mercury 70 is of less quantity than the body of mercury 61 in Fig. 4, being at a lower normal liquid level 71 so that the solid tubular body 60 in Fig. 7 has a normal floating position intermediate the two ends of the annular chamber 32. Thus at the normal position of the solid tubular body 60 in Fig. 7 the solid tubular body has freedom for vertical longitudinal movement in both directions. It is apparent that vertical movements of the drill column of relatively low magnitude will merely cause the float 60 in Fig. 7 to bob up and down without the float reaching either end of the annular space. This bobbing action will be resisted by inertia, friction and by a dashpot action, all of which tend to modify vibratory and shock forces in a desirable manner. Vertical movements of the drill column of relative large amplitude will cause the solid tubular body 60 of Fig. 7 to reach one or both ends of the annular chamber 32 to make impact against the solid structure of the drill column.

The individual drill collar 25e shown in Fig. 8 is of the same construction as heretofore described except for the contents of the annular chamber 32. In this instance, the

annular chamber 32 contains a mass 72 of solid material in the form of relatively small bodies. The mass 72 may comprise, for example, relatively small steel balls. This mass 72 of bodies of solid material is immersed in a liquid body 73 of relatively low specific gravity, for example, water, the liquid body having a normal level 74 spaced substantially below the upper end of the chamber.

This embodiment of the invention shown in Fig. 8 operates in much the same manner as the embodiment shown in Fig. 6, since in both instances a mass of solid material is normally at the bottom of an annular chamber containing a liquid. It is to be noted, however, that when such a mass of small bodies is thrown upward from the bottom of the annular chamber, the individual bodies of the mass tend to separate so that the return impact of the mass against the bottom of the annular chamber is attenuated less severe than the sharp return impact of a solid body. Another difference is that the mass of small bodies forms numerous tortuous passages for relatively great resistance to displacement flow of the liquid when the mass shifts vertically in the annular chamber.

The liquid body 73 may be omitted in the form of the invention shown in Fig. 8 if desired. If the liquid is omitted the individual bodies making up the mass of solid material will still tend to separate when the mass is lifted from the bottom of the annular chamber. Here again, the return downward movement of the solid material will result in less severe impact against the lower end of the annular chamber than would occur if the solid material were all in one piece.

The individual drill collar 25f of Fig. 9 is similar to the individual drill collar of Fig. 8 but in this instance a mass 80 of small solid bodies for example, steel balls, floats on a body of mercury having a normal liquid level 81. In this instance, the liquid level is high enough to force the mass 80 against the upper end of the annular chamber 32. Thus the arrangement shown in Fig. 9 is the reverse of the arrangement shown in Fig. 8 in that the mass of small bodies responds primarily to downward thrusts on the part of the drill collar instead of upward thrusts. The same dashpot effect is present in both Figs. 8 and 9.

It is apparent that a drill collar assembly such as the drill collar assembly 24 of Fig. 1 may comprise a variety of individual drill collars 25, the variety including any of the individual drill collars shown in Figs. 2, 4, 6, 7, 8 and 9 or similar individual drill collars. For example, a drill collar assembly 24 may include the individual drill collars 25b, 25c and 25d of Figs. 4, 6 and 7 respectively. Thus in some of the individual drill collars such as the individual drill collar shown in Fig. 4, the relatively movable material will respond primarily to downward thrusts of the drill column; in other individual drill collars such as the individual drill collar shown in Fig. 6 the relatively movable material will respond primarily to upward thrusts of the drill column; and in still other individual drill collars such as the individual drill collar shown in Fig. 7 the relatively movable material in seeking a normal intermediate position will have a relatively mild and yielding action with respect to low amplitude movements of the drill column but will fully oppose movements of relatively large magnitude. The individual drill collars of Figs. 8 and 9 may be added to such a drill collar assembly or may be substituted for individual drill collars of Figs. 6 and 4 respectively. As heretofore pointed out, the individual drill collars of Figs. 8 and 9 operate with less violent impact of the solid material against the ends of the annular chambers and in addition are characterized by a modified dashpot action.

My description in specific detail of selected practices of the invention will suggest various changes, substitutions and other departures from my disclosure that properly lie within the spirit and scope of the appended claims.

I claim:

1. A drill collar for connection between upper and

lower portions of a drill column, said upper and lower portions extending upwardly to a rotary table and downwardly to a drill bit, respectively, said drill collar both providing weight for downward pressure on the drill bit and for minimizing the transmission of vibration and shock forces from the drill bit to the drill column, said drill collar comprising: inner tube means having a longitudinal flow passage for communication with the drill column, upper coupling means fixed to the upper end of said inner tube means and adapted for connection with the lower end of said upper portion of said drill column, lower coupling means fixed to the lower end of said inner tube means and adapted for connection with the upper end of the lower portion of said drill column, outer tubular means having an upper end also connected to said upper coupling means and having a lower end connected to said lower coupling means, said outer tubular means surrounding at least a portion of said inner tube means and being spaced a predetermined distance therefrom to form a chamber therewith, a passageway extending from the exterior into the interior of said chamber, said chamber containing a selected medium comprising at least a liquid, said liquid only partially filling said chamber, means to provide a liquid-tight seal for said chamber including means to seal said passageway, whereby vibratory and shock forces transmitted to said coupling means will be at least in part transmitted to said medium, the turbulence of said liquid created by the flow thereof in said chamber thereby dissipating at least some of the energy of said vibratory and shock forces.

2. The invention as defined in claim 1, wherein said selected medium comprises both a liquid and solid material, the specific gravity of said solid material being different from that of said liquid material, whereby vibratory and shock forces transmitted to said coupling means will be at least in part transmitted to said solid material and to said liquid material for movement of one relative to the other and independently of said coupling means, the turbulence of said liquid material created by the flow thereof past said solid material thereby dissipating at least some of the energy of said vibratory and shock forces.

3. The invention as defined in claim 2, wherein said solid material is a single solid body having a shape to permit its movement vertically in said chamber.

4. The invention as defined in claim 2, wherein said chamber is an annular chamber, and wherein said solid material is a hollow tube to fit in said chamber but being spaced at least from one of the means defining said chamber and being vertically movable therein.

5. The invention as defined in claim 4, wherein said solid material has a specific gravity less than that of said liquid material.

6. The invention as defined in claim 4, wherein said solid material has a specific gravity greater than that of said liquid material.

7. The invention as defined in claim 2, wherein said solid material includes a plurality of particles, the maximum dimension of each of which is small in comparison to the size of the dimensions of said chamber.

8. The invention as defined in claim 7, wherein said solid material has a specific gravity less than that of said liquid material.

9. The invention as defined in claim 7, wherein said solid material has a specific gravity greater than that of said liquid material.
